E. MENZ

AUTOMATIC ACETYLENE GENERATOR

Filed Dec. 18, 1926

Inventor:

Emil MINT.

UNITED STATES PATENT OFFICE.

EMIL MENZ, OF BERLIN-FRIEDENAU, GERMANY.

AUTOMATIC ACETYLENE GENERATOR.

Application filed December 18, 1926, Serial No. 155,712, and in Germany November 17, 1925.

This invention relates to an automatic acetylene gas generator of the water-to-carbide type and of the kind composed of two communicating water tanks in one of which a gas bell is arranged to float while the other contains a gas generating chamber, a gas delivery pipe which leads from the generating chamber to the gas space under the bell and which rises vertically through the latter, being provided with a valve which is controlled by the bell and which, when closed thereby causes the gas to flow through a by-pass into the bell under increased pressure. In a known device of this type the normal delivery pipe is provided with a stop cock arranged outside the bell and operated by a device on the latter, and the by-pass is formed by an auxiliary delivery pipe arranged separately from the normal one, the gas being in each instance delivered into the water space through caps arranged over and concentrically with the pipes.

The object of the present invention is to simplify the arrangement and provide a more sensitive valve arrangement which only requires a very slight movement of the bell for its operation, and the invention consists essentially in the provision of a vertically movable valve element arranged inside the bell and adapted to cooperate with the nozzle of the delivery pipe and keep the latter normally closed, said valve being normally disconnected from the bell, means being provided whereby the bell, at a given point of elevation, acts on the valve for opening and reclosing the same. This arrangement ensures the opening and reclosing of the valve by a movement of the bell through the extent of a few millimeters and removes a defect which is quite common in the automatic acetylene generators at present in use, viz, that of inertness, the gas generation being slow to start as well as to cease so that oxygen is wasted at the commencement of an operation while a dangerous escape of acetylene gas occurs after the operation.

As the pipe opens direct into the gas space, the by-pass can be arranged concentrically with the same pipe, apertures being provided in the latter through which the gas enters the by-pass when the valve is closed. In this manner a very simple arrangement is obtained.

The invention is illustrated in the accom-

panying drawing which represents a vertical section of the gas generator.

The gas generator is composed of two interconnected water tanks *a* and *c*, a gas purifier *d* and a chamber *e* serving as a safety escape. The tank *a* is the gas holder and contains a floating bell *b* which rises and falls with the gas pressure. The tank *c* contains a gas generation chamber in the form of a vessel *i* which is inverted over the carbide cage *g* and which communicates through pipes *h* and *n* with the gas delivery pipe *k*. The water tends to rise through the chamber *i* into contact with the carbide, the pressure of the generated gas keeping it back more or less according to the gas consumption. From the bell *b*, the gas is led through a pipe *r* or to the purifier and thence through the chamber *e* to the place of consumption.

According to the invention, a valve *V* is provided for closing the delivery pipe *k*, and this valve is controlled by the bell *b* which closes the valve on rising and opens the same on descending. When the pipe *k* is thus closed owing to interrupted gas consumption, the gas is led through a by-pass *s* into the water space under the bell *b* where it has to suppress a water column of the depth *S*. The resistance of this water column increases the pressure in the chamber *g* and causes the water to recede rapidly from the carbide so as to stop the gas generation. As soon as the valve *V* is reopened by the bell *b* owing to renewed gas consumption, the pressure will be relieved, and the water will rapidly re-ascend into contact with the carbide so as to restart the gas generation.

The pipe *k* rises vertically through the bell from a counter-pressure chamber *f* into which the pipe *n* is led. The by-pass *s* is concentric with the pipe *k* and communicates with the latter at its upper end at *B*, the lower end opening into the water space at the distance *S* from the water head. The valve *V* has its seat on the upper end of the pipe *k* and is carried by a sleeve *c* arranged concentrically with the pipes *k* and *s*, air vents being provided at the upper end of the sleeve. The latter, which closes the valve by gravity, is normally supported on a double-armed lever *H* which cooperates with a ring *R* carried by the bell *b*. As the bell descends, the ring *R* engages and rocks the lever so as to raise the sleeve *c* and open the valve. As the bell rises

the ring is lifted off the lever so that the sleeve is allowed to sink and close the pipe *k*.

The rapid fluctuations of the water surface in the gas generation chamber *g* has the further advantage that the residual lime will be effectively washed away from the carbide so that on the one hand the water will have immediate access to the carbide and so that on the other hand there will be no belated generation of gas by water-retaining deposits.

I claim:

1. In an automatic acetylene gas generator of the character described, the combination with a gas bell and with a gas delivery pipe which rises vertically through the bell and opens direct into the gas space of the latter, of a vertically movable valve element arranged in the gas space of the bell and adapted to operate with the nozzle of the pipe and keep it normally closed, said valve being normally disconnected from the bell, and controlling means cooperating with the bell and enabling

the latter, at a given point of elevation, to act on said valve for opening and reclosing the same.

25

2. A device as claimed in claim 1 wherein the controlling means comprise a ring carried by the gas bell, a sleeve carrying the valve element and arranged concentrically with the gas delivery pipe, and a double-armed lever pivoted to said pipe so as to support the sleeve with one arm and bear against said ring with the other arm.

30

3. The structure claimed in claim 1 in combination with a sleeve arranged concentrically with the gas delivery pipe and forming a tight closure with the upper end thereof, the delivery pipe being formed with lateral apertures through which it communicates with said sleeve so as to feed the gas through the latter when the upper end of the pipe is closed.
